UNITED STATES PATENT OFFICE.

PAUL H. WELCKER, OF ST. PAUL, MINNESOTA, ASSIGNEE TO BROWN & BIGELOW, OF ST. PAUL, MINNESOTA, A CORPORATION OF MINNESOTA.

DESK FILE AND TRAY.

Application filed September 17, 1920. Serial No. 410,849.

To all whom it may concern:

Be it known that I, PAUL H. WELCKER, a citizen of the United States, residing at St. Paul, in the county of Ramsey and State of Minnesota, have invented a new and useful Improvement in Desk Files and Trays, of which the following is a specification.

This invention relates to a desk file and tray, designed with a compartment for index cards and having associated therewith a space for memorandum blank sheets which can be used for making notations and filed under the desired index for future reference. A feature of the invention is the simple design wherein the blank memorandum sheets are readily accessible together with the index file so that one can refer to the file to refresh their memory of any notations therein whenever it is desired. This means of filing memorandums provides a neat and attractive desk file which makes a desirable office utility.

The invention further includes tray means associated with the file for clips or pins, which can be used to hold the memorandum sheets together. The tray portion of the file forms a base of a suitable nature to support the index compartment above the same. In an article of this nature it is essential to provide a construction having a neat appearance and the outlines of which are designed to give a device which is pleasing to the eye.

The compartments of the file are preferably made of metal stampings of a simple nature, easily put together; however, other material can be used to accomplish a similar design with the same functions.

In the drawing forming a part of the specification:

Figure 1 is a perspective view of the desk file and tray.

Figure 2 is a section on the line 2—2 of Figure 1.

Figure 3 is a plan view of the file.

Figure 4 is a sectional elevation on the line 4—4 of Figure 3.

Figure 5 is a geometrical development of the portion forming the base of the file and tray.

Figure 6 is a front elevation partly in section of an alternative construction.

Figure 7 is a section on the line 7—7 of Figure 6.

The device A includes the index file com-

partment B and the tray compartment C, each of which are associated together to form an attractive desk utility wherein memorandum sheets and clips are readily accessible to be used together or as may be desired to perform the functions of a reminder desk file and office utility.

The compartment B is formed in a rectangular shape from a piece of sheet material so as to conform with the size of the cards used for the indexed file D, which can be of any suitable nature, having the index tongues projecting above the compartment so as to be easily engaged and separated in the ordinary well known manner. The compartment B has a suitable space in back of the file D for blank sheets 10, which may be used for memorandum notations and which are of a suitable size and shape to fit and be concealed when inserted in the file D. The blank sheets 10 are ordinarily practically concealed back of the file D, but are readily accessible so that a sheet can be removed and used for notations, then be put on the file D under the desired heading or index. The compartment B is large enough to allow the cards of the file D to ordinarily lean against the memorandum sheets 10. This has a tendency to conceal the sheets back of the file.

The front face of the compartment B forms a suitable space for receiving a calendar E, the sheets of which are held by suitable tongues stamped from the front face of the compartment and bent to hold the sheets of the calendar freely removable so that the different months can be displayed or a new calendar pad can be inserted.

The tray C forms the base portion of the device A, the main portion of which is cut from a single piece of sheet material such as the stampings 12, illustrated in the geometrical development in Figure 5. The portion 12 is bent along the dotted line 13 to form the base into the shape illustrated in Figures 1 and 2. The sides 15 of the base flare outwardly and the lower edge of the same is bent inwardly to form a smooth flange 16 extending about the lower edge of the base to form a smooth surface for it to rest on. This construction provides means which will not scratch a desk or other surface on which the device is adapted to rest.

The portion 12 is cut away to form open-

ings 17, as illustrated in Figure 5, forming lips 18 and tongues 19. The lips 18 are bent downward on the dotted lines 20 and are adapted to form the side wall of the compartments 21 of the tray C, while the tongues 19 are bent to extend in a downward direction and engage to form supporting means for the bottom 22 of the tray compartment. The bottom 22 is held in a curved position and thus provides a suitable construction so that clips or pins held in the tray compartments 21 can be easily removed.

The supporting tongues 23 are cut from the portion 12 and bent upward so as to engage and support the inner surface of the compartment B. These tongues are spot-welded or otherwise attached to the side of the compartment B so as to rigidly connect the file compartment and base of the device A together. The construction of the device A is very simple and when formed of metal stampings consists of three parts which are easily assembled and form a practical desk utility with a desirable design.

Figures 6 and 7 illustrate the device A formed with a cardboard card index compartment B which is covered with mission leather F or other suitable material, while the body or the base of the tray C, is formed of wood or other desirable material and is covered with mission leather G or any other material which may be desired. In this construction the compartments perform the same function as that illustrated in Figures 1 and 2. Mission leather is used very extensively for office utilities and therefore it may be desirable to make the device A in this manner.

In accordance with the patent statutes I have described the principles of operation of my invention together with the construction which I believe to represent the best embodiment thereof, but I desire to have it understood that the drawings are only illustrative and that the invention can be carried out by suitable means within the scope of the following claims:

I claim:

1. A device of the class described comprising a base portion stamped from sheet material, downwardly extending lips adapted to form side walls for compartments, a separate bottom portion for the compartments, tongues in said base portion adapted to support said bottom, a card index com-

partment adapted to be supported by said base formed from sheet material and tongues projecting from said base adapted to engage and support said card index compartment. 60

2. A desk file tray formed from sheet material comprising, a base portion having flaring side walls, a smooth edge formed along the bottom of said side walls, means adapted to divide said base into compartments, a card index compartment adapted to be supported by said base, and lugs projecting up from said base to support and hold said card index compartment connected thereto. 70

3. A desk file tray including, a sheet metal base portion bent to form the outwardly flaring side walls, tray openings formed in said base portion, a curved tray bottom adapted to be supported in said base portion, division walls formed integral with said base portion and adapted to engage said curved bottom to form the side walls of compartments in said base and a card index file compartment secured to said base portion extending over a portion of said tray openings. 75

4. A device of the class described comprising a base portion stamped from sheet material, downwardly extending lips adapted to form side walls for compartments, a separate bottom portion for the compartments and tongues in said base portion adapted to support said bottom against said downwardly depending lips. 85

5. A desk tray formed from sheet material comprising a base portion having depending side walls, tray openings formed in said base portion, a curved tray bottom adapted to be supported in said base portion and division walls formed integral with said base portion and adapted to engage said curved bottom to form the side walls for said tray openings. 95

6. A desk tray including a sheet metal base portion formed from a single piece of material, tray openings formed in said base portion, a curved bottom for said tray openings, lugs formed integral with said base portion, adapted to hold said tray bottom in position in said base, and side walls formed integral with the body of said base portion and curved to fit in close proximity with said tray bottom forming a closed joint between said curved tray bottom and the edge 100 of said side walls. 110

PAUL H. WELCKER.
